UNITED STATES PATENT OFFICE.

THOMAS GANDERTON, OF BEAVER, PENNSYLVANIA, ASSIGNEE TO MARTIN HUSSEY,
OF CLEVELAND, OHIO.

AUTOMATIC CONTROL FOR INTAKE PASSAGES.

Application filed October 10, 1921. Serial No. 506,850.

To all whom it may concern:

Be it known that I, THOMAS GANDERTON, a citizen of the United States, and resident of Beaver, in the county of Beaver and State of Pennsylvania, have invented certain new and useful Improvements in Automatic Controls for Intake Passages, of which I hereby declare the following to be a full, clear, and exact description, such as will enable others skilled in the art to which it appertains, to make and use the same.

The invention relates to means for supplying additional air to the explosive mixture of the engine of a motor car when the car is moving up an incline, in order to increase the amount of power developed by the engine proportionately to the increased demand made upon the engine to overcome the grade.

20 The invention includes an automatically acting air valve, by means of which the air is supplied in proportion to the steepness of the grade, and also includes a valve operated by the action of a pendulum to close the valve more or less completely, according to the steepness of the grade, as the machine is ascending the grade, and to open the valve when the machine is moving down the grade to permit the introduction of a volume of 25 air, determined by the steepness of the grade, the action of the pendulum being such as to open the valve more or less and to supply air to weaken the explosive mixture, when the machine is travelling on the level, 30 and to retain it open on a down grade, since no power will be required when moving down grade.

The invention further includes a horizontal projecting air passage or tube, inserted 40 in the intake passage of the cylinders and a sleeve valve rotatable thereon, the aforesaid sleeve valve being automatically operated by the action of a pendulum to open and close opposed air inlet ports located in said 45 valve and tube respectively.

The invention further includes means for preventing opening of the valve when the car is moving up hill.

The invention is hereinafter further described, shown in the accompanying drawings, and specifically pointed out in the claim.

In the accompanying drawings, Fig. 1 is a side elevation of the intake manifold, showing the pendulum actuated valve; Fig. 2 is

an enlarged view of the valve; Fig. 3 is a longitudinal section thereof; Fig. 4 is a transverse section thereof.

In these views, 1 represents the intake manifold; 2 is an air inlet tube, the inner end of which is inserted in the opening, 6, in the manifold.

The tube, 2, is closed at the outer end, and provided with radial perforations or ports, 5^a, 5^a, for air admission. Upon the projecting portion of the air tube is positioned the valve sleeve, 4, which is provided with corresponding air admission perforations, or ports, 5, 5.

A pendulum weight, 3, is attached to the valve sleeve. In action, when the car is ascending an incline, the pendulum will restrain the valve from movement while the air inlet tube will rotate, thus closing the air inlet ports, but when the car is moving on a down grade, the valve tube will rotate to cause the ports or perforations in the tube and sleeve to register with each other and admit air to the explosive mixture from the carburetor.

A lug or pin, 12, upon an annular enlargement of said tube, engaging a shoulder, 11, upon the sleeve, causes the sleeve to rotate with the air admission tube and prevents the opening of the ports when the car is ascending a grade, and a shoulder, 11^a, spaced therefrom, engages the pin, 12, when the car is moving on a down grade, and prevents the sleeve from closing the ports, 5 and 5^a. The pin conveniently enters a recess, 90 having the shoulders, 11 and 11^a, upon its opposite sides.

The action of this device is altogether automatic and requires no attention. The sleeve is preferably retained in place upon the air admission tube by means of a spring, 7, washers and pin, 8 and 9, and a shoulder, 10, upon the air tube.

Having described the invention, what I claim as new and desire to secure by Letters Patent, is:

In an automatically acting valve for an auxiliary air outlet, to the intake manifold of an explosion engine, the combination with a flanged carburetor outlet pipe, of a tube, the inner end of which is inserted in an opening in the manifold, said tube being closed at its outer end and provided with aligned radial ports for air admission, a valve sleeve mounted upon the projecting

portion of the air tube, said sleeve provided with corresponding air admission ports, a pendulum weight attached to said sleeve, a coiled spring upon the projecting extremity 5 of said tube, retaining means therefor upon the extremity of said tube, a washer between said tube and sleeve, a lug upon an enlarged portion of said tube, and a recess in the end of said sleeve, said lug entering said 10 recess, and positioned to engage one side of said recess when said tube is rotated as the engine is tilted to ascend an incline, to pre-

vent the opening of said ports, and to engage the other side of said recess when the engine is descending an incline, to prevent 15 the closing of said ports, substantially as described.

In testimony whereof, I hereunto set my hand this 29th day of August, 1921.

THOS. GANDERTON.

In presence of—

CHAS. F. SIPE,
EDWARD J. LENAHAN.
